(57) **CLAIM**

We claim the ornamental design for a circular saw shoe, as
shown and described.

DESCRIPTION

FIG. 1 is a front perspective view of a circular saw shoe in
accordance with our new design.

FIG. 2 is a left-side view of the circular saw shoe of FIG. 1.
FIG. 3 is a right-side view of the circular saw shoe of FIG.
1.

FIG. 4 is a front view of the circular saw shoe of FIG. 1.
FIG. 5 is a rear view of the circular saw shoe of FIG. 1.
FIG. 6 is a top view of the circular saw shoe of FIG. 1; and,
FIG. 7 is a bottom view of the circular saw shoe of FIG. 1.
The portions of the circular saw shoe shown in broken lines
are included for the purpose of illustrating environment and
form no part of the claimed design. The portions of the
circular saw shoe shown in broken lines having unequal
length segments illustrate the boundary of the claimed
design and form no part of the claimed design.
